HENRI ALPHONSE NOALHAT AND GEORGES FOURNIER, OF PARIS,
FRANCE.

AUTOMOTOR-TORPEDO.

No. 807,195.

Specification of Letters Patent.

Patented Dec. 12, 1905.

Application filed May 5, 1905. Serial No. 259,054.

To all whom it may concern:

Be it known that we, HENRI ALPHONSE NOALHAT and GEORGES FOURNIER, citizens of the Republic of France, and residents of Paris, France, have invented new and useful Improvements in Automotor-Torpedoes, which improvements are fully set forth in the following specification.

This invention has for its object an automotor-torpedo in which the motor mechanism is broadly constituted by two, three, or more fly-wheels arranged in such a manner that at the beginning of the trajectory of the torpedo one only of these fly-wheels exerts a driving effort, the second exerting such action in conjunction with the first as soon as the velocity of this first fly-wheel slackens in a certain proportion and the third likewise exerting a driving effort in conjunction with the first two when the velocity of these latter also diminishes to a predetermined extent. The driving effect of these fly-wheels upon the torpedo may be increased by the motor effect of a turbine suitably connected therewith.

In the accompanying drawings, Figure 1 is a longitudinal section through the torpedo-motor mechanism comprising three fly-wheels. Fig. 2 is a cross-section through one of the fly-wheels. Figs. 3 and 4 represent, upon a larger scale, mechanism for driving the motor-shaft by one of the fly-wheels.

The fly-wheels $A A' A^2$ are turned from three bars of steel of high quality and perfectly homogeneous in such a manner that their center of gravity exactly coincides with the axis of rotation, which is at their center. They are adjusted and supported at the extremities of their axis by the ball-bearings $a a' a^2$, the fixed cups of which are screwed and locked in the brackets $b b' b^2$, Fig. 1, which are themselves adjusted around and fixed upon the sole-plates of the brackets $E E' E^2$. Upon each of the fly-wheels there are centered and bolted pairs of bevel-pinions $B B' B' B^2$, meshing with the bevel-pinions $C C' C^2$, mounted upon pairs of shafts each lettered $D D' D^2$, parallel with the axis of the torpedo and at the extremities of which are situated the spur driving-pinions $C' C' C^2$

of the speed-reducing gear of the propeller-shafts. The gear ratios $\frac{B}{C} \frac{B'}{C'} \frac{B^2}{C^2}$ are different in such manner that $\frac{B}{C}$ is greater than $\frac{B'}{C'}$, which is itself greater than $\frac{B^2}{C^2}$.

The pairs of shafts $D D' D^2$ being similar, it is only necessary to describe one of them. It is composed of three lengths, each terminating in plates $F F' F^2$. The front length is connected with the middle length by the Oldhan joint g' , and the middle length is connected with the rear length by the Oldhan joint g^2 . The centering and the rotation of the shafts and of the pinions C are effected by means of ball-bearings $d e$, the fixed cups of which are themselves centered in the brackets $E E' E^2$. These latter are solid with the shell of the torpedo, as indicated in Fig. 1.

In each of the gear-wheels $C C' C^2$ are fixed, by means of bolts h , Fig. 4, the steel crowns $H H' H^2$, Figs. 1, 3, and 4, and upon the turned periphery of these crowns are cut grooves i , intended for the reception of a ball of cemented steel j and a spring h' . This is the form of clutch universally known as a "free-wheel" clutch. This device may of course be replaced by any other form of clutch—such as a ball-clutch, a roller-clutch, a pawl-clutch, or the like.

The operation of the apparatus is as follows: The three fly-wheels $A A' A^2$ are started at the moment at which the torpedo is despatched, as in the Howell torpedo, at a velocity of about twelve thousand revolutions per minute. This starting is effected, as in the old form of torpedo, by means of a small shaft and of the gear-wheel p , Fig. 2. It should be remembered that $\frac{C}{B}$ is smaller than $\frac{C'}{B'}$ and smaller than $\frac{C^2}{B^2}$.

For the sake of clearness let us assume that the ratio $\frac{C}{B}$ is equal to 1, the ratio $\frac{C'}{B'}$ equal to 1.8, and the ratio $\frac{C^2}{B^2}$ equal to 2.5. On starting we shall have the velocities—

Crown H.....	12,000 revolutions.
Crown H ¹ $\frac{12,000}{1.8}$ revolutions.....	6,666 revolutions.
Crown H ² $\frac{12,000}{2.5}$ revolutions.....	4,800 revolutions.

5 In these conditions, on starting, the fly-wheel A will alone exert a motor action and the others will be loose relatively to the shaft D D' D², and this will continue until the velocity of the fly-wheel A has fallen to six 10 thousand six hundred and sixty-six revolutions per minute. From this moment the two fly-wheels A A' will work together, so that the velocity curve will fall less rapidly. The attack of the second fly-wheel will take 15 place without shock, with the sweetness of two equal gears, the velocity curves of which endeavor to mingle or coincide in inclining gently to a common tangent. Then the energy of these two fly-wheels is decreasing, the shaft 20 D D' D² will gradually attain the velocity of four thousand eight hundred revolutions per minute, this velocity corresponding with that of the third crown, and the three fly-wheels will then coöperate in the propulsion of the 25 torpedo.

This motor mechanism presents the advantage of furnishing an almost constant velocity for a great part of its travel, largely increasing the radius of action of the torpedo by insuring for it a trajectory which is almost rectilinear, owing to the powerful gyroscopic effect of the three fly-wheels.

It is obvious that the turbine may be combined with any one of the torpedo fly-wheels. 30 It should likewise be understood that each of the fly-wheels may be combined with a turbine. The opening of the motor-fluid reservoirs serving to actuate the turbine or turbines may be effected automatically by any 40 appropriate means at any desired point in the trajectory of the torpedo.

Having now particularly described and ascertained the nature of our said invention and in what manner the same is to be performed, 45 we declare that what we claim is—

1. The combination with an automotor-torpedo, of a plurality of fly-wheels adapted to receive rapid rotation at the moment at which the torpedo is started, the propeller-shafts 50 composed of several sections or lengths which in number correspond with that of the fly-wheels and which are connected with each other by suitable joints, said joints enabling

the first section or length to drive the second, the latter to drive the third section or length, 55 sets of gear-wheels for the transmission of movement from each fly-wheel to the corresponding section or length of the propeller-shaft, the ratio of the set of gear-wheels of the first fly-wheel being greater than that of the set of gears of the second fly-wheel, the ratio of the set of gears of the latter being again greater than that of the set of gears of the third fly-wheel, a clutch-coupling between the set of gears of each fly-wheel and the corresponding section or length of the propeller-shaft to permit transmission of movement from each of the fly-wheels to the corresponding section or length of the propeller-shaft at a desired moment, substantially and for the 70 purpose as specified.

2. The combination with an automotor-torpedo, of a plurality of fly-wheels adapted to receive rapid rotation at the moment at which the torpedo is started, the propeller-shafts 75 composed of several sections or lengths which in number correspond with that of the fly-wheels and which are connected with each other by suitable joints, said joints enabling the first section or length to drive the second, the latter to drive the third section or length, bevel gear-wheels keyed upon the shaft of each fly-wheel and bevel gear-wheel mounted upon each section or length of the propeller-shafts and meshing with the bevel gear-wheel 85 of the corresponding fly-wheel, the ratio of the intermeshing gear-wheels of the first fly-wheel being greater than that of the intermeshing gear-wheels of the second, and the ratio of the intermeshing gear-wheels of the latter being greater than that of the third fly-wheel, a clutch-coupling between each bevel gear-wheel of the propeller-shafts and the corresponding section or length of the latter 90 for the transmission of movement from each of the fly-wheels to the corresponding sections or lengths of the driving-shafts, substantially and for the purpose as specified.

In testimony whereof we have signed this specification in the presence of two subscribing witnesses.

HENRI ALPHONSE NOALHAT.
GEORGES FOURNIER.
